UNITED STATES PATENT OFFICE.

WILLIAM WINDFIELD RHEA, OF BARTELSVILLE, OKLAHOMA.

WELL-PACKER.

1,188,489.

Specification of Letters Patent. Patented June 27, 1916.

Application filed July 17, 1915. Serial No. 40,415.

To all whom it may concern:

Be it known that I, WILLIAM W. RHEA, a citizen of the United States, and a resident of Bartelsville, in the county of Washington and State of Oklahoma, have invented a new and Improved Well-Packer, of which the following is a full, clear, and exact description.

My invention relates to well packers of a type suitable for preventing the escape of gas from a deep well, and is adapted for use upon gas wells, oil wells, and deep earth borings generally.

More particularly stated, I seek to produce a well packer provided with means for effectively preventing the passage of gas through the packer and parts adjacent thereto, and also having a maximum amount of mechanical strength for the purpose of resisting vast pressures, such, for instance, as may be caused by water and oil accumulating within the well.

My invention further contemplates a packer which is of comparatively rigid construction and preferably made of metal throughout; and adapted to be used with a packing made largely, if not entirely, of resilient and flexible material, such as soft rubber.

It sometimes happens that in gas wells the working pressure of the gas (sometimes designated as the rock pressure of the gas) may drop to a comparatively low degree. If, now, the well contains a considerable volume of oil or water, and the only packer used happens to be a so-called rubber packer, the pressure of the liquid may force the rubber downward and cause the packer to leak. This is exceedingly liable to happen in instances where the rubber packer from age has become rotten, or at least degenerated in strength. Again, pieces of rubber are sometimes detached from the rubber packer and blown out through the tubing by the gas escaping under pressure.

My improved packer may, if desired, be employed in connection with any well known form of rubber packer, and placed below the latter in such manner that any hydrostatic pressure likely to develop at the bottom of the well is insufficient to force the rubber packer downwardly. That is to say, the hydrostatic pressure being effectively supported upon my improved packer, and the latter being disposed below the rubber packer, the rubber packer is not subjected

to undue strain dependent upon hydrostatic pressure.

Reference is made to the accompanying drawings forming a part of this specification, and in which like letters indicate like parts.

Figure 1 is a side elevation showing my improved metallic packer and parts immediately associated therewith, as used upon tubing, and as they appear when the packer is first let down and before it is rendered gas-tight; Fig. 2 is a vertical section through the mechanism appearing in Fig. 1, and is taken upon the line 2—2 of Fig. 4, looking in the direction of the arrows; Fig. 3 shows the parts as they appear after the column of tubing is lowered into its resting position, thus rendering the packer gas-tight; also shows the addition of a rubber packer; Fig. 4 is a section on the line 4—4 of Fig. 2, looking in the direction of the arrows; and Fig. 5 is a section on the line 5—5 of Fig. 3, looking in the direction of the arrows.

Well casing is shown at 6 and has the general form of a cylinder. A pipe section 7 is provided at its upper end with an internally treaded portion 8, the latter engaging a reduced portion 10 of a sleeve 9, the reduced portion 10 being threaded externally at 11 for mating the adjacent threaded portion 8 of the pipe section 7. The sleeve 9 at its upper end is provided with a massive portion 12, of large diameter, this portion being threaded internally. A bushing 13 having a generally annular form is provided with a portion 14 of reduced diameter, which fits into the enlarged portion 12 of the sleeve 9. A hollow cone 15 is provided with a tubular portion 16, which extends downwardly through the opening 13^a in the annular bushing 13. A jam nut at 17 is threaded internally and fitted upon the lower end of the tubular portion 16. This jam nut has such diameter that it may move vertically within the sleeve 9, but it is unable to pass upwardly through the passage 13^a of the bushing 13, as may be understood by contrasting Figs. 2 and 3. The cone 15 at its upper end is provided with an externally threaded portion 18 of reduced diameter. Above the cone 15 is a nipple 19, having at its lower end an enlarged portion 20, which is threaded internally and fitted upon the portion 18 of the cone. A section of well tubing is shown at 21, and is threaded at its lower end, which fits into the up-

110

per end of the nipple 19, the latter being threaded to receive it. In some instances I provide a rubber packer 22, of the usual or any desired construction, and mount the 5 same upon the nipple 19, as indicated in Fig. 3. This packer fits tightly within the casing 6, and its specific mechanism constitutes no part of the present invention. I provide a number of gripping sectors 23, 24, 10 25, each of these sectors being of arcuate cross section and comprising an arcuate span of 120 degrees. The sectors 24 are in this instance of double the thickness of the sectors 23 and 25. The three sectors 23, when 15 placed together as indicated in Figs. 4 and 5, together constitute a fragmentary ring. Below this ring the three sectors 24 together constitute another ring, and below this ring a third ring is formed by the three sectors 20 25. The composite rings thus formed are separated by gaskets 26, 27 of soft lead or other equivalent material. Extending through the various sectors and the gaskets 26, 27 are guide bolts 28, and mounted upon 25 the lower ends of the latter are nuts 29. The guide bolts extend vertically through slots 30, with which all of the gripping sectors are provided. The several gripping sectors are provided externally with gripping surfaces 31 of arcuate form, these surfaces being such as to readily engage against the inner wall of the casing 6.

The various sectors are adapted to have a little relative movement, such as may be permitted by the guide bolts within the slots 30, 35 as may be understood by contrasting Figs. 4 and 5. Owing to this slight play between the sectors, slots 32 may be formed between them, as indicated in Fig. 5. The various 40 gripping sectors are so arranged as to break joints, as indicated in Fig. 1; that is to say, the gripping sectors 23 and 25 are staggered relatively to the gripping sectors 24. A rivet 33 extends radially inward through one of 45 the gripping sectors 25, and also through the wall of the adjacent tubular portion 16 of the cone 15. This rivet at its point of connection with the tubular portion 16 is disposed some distance below the slanting 50 portion of the cone 15, as indicated in Fig. 2. The purpose of the rivet is to hold the entire group of gripping sectors rigid relatively to the cone 15, and spaced slightly therefrom, as indicated in Fig. 2, until the 55 conical parts here shown are let down into the well, so that the weight of the sleeve 19 and parts below it rest upon the well bottom. This done, and the cone 15 and parts above it moving a little farther downward, 60 the rivet 33 is sheared off or broken, and the cone 15 is brought into direct engagement with the inner surfaces of all of the gripping sectors.

The gripping sectors, considered as a 65 group, have collectively a form which may

be described as externally cylindrical and internally conical. The internally conical surface appears at 24^a in Fig. 2, and is adapted to fit gas-tight around the external surface of the cone 15 when this cone occupies its lowermost position, as indicated in Fig. 3.

The operation of my device is as follows: The parts being assembled and arranged as indicated in Fig. 2 and being let down into 75 the well, when the pipe section 7 engages the bottom of the well, the sleeve 19 is brought to a halt; then, by the further descent of the cone 15 and parts associated with it, the rivet 33 is sheared off or broken 80 and the cone 15 is seated against the conical surface 24^a of the entire group of gripping sectors. This causes the gripping sectors to move slightly apart from each other; or, in other words, the slots 32 to be widened. 85 The outer gripping surfaces 31 of the gripping sectors are thus forced tightly against the adjacent inner surface of the well casing 6, and the packer is rendered gas-tight. If now, owing to an accumulation of water or 90 oil within the well, a considerable hydrostatic head is developed, this pressure is effectively withstood by my improved packer above described. The rubber packer 22 may be used or not, as above described. If it is 95 used, it serves merely as an auxiliary device for preventing the escape of gas. It is not subjected to any appreciable measure of hydrostatic pressure.

I do not limit myself to the precise construction shown, as variations may be made therefrom without departing from the spirit of my invention.

Having thus described my invention, what I claim as new and desire to secure by 105 Letters Patent is as follows:

1. In a well packer, the combination of a plurality of superimposed ring-like members each formed of a plurality of gripping sectors made of metal and provided with 110 gripping surfaces for engaging the inner surface of the well casing, said gripping sectors together having an internal surface which is approximately conical, and a hollow member having externally the form of 115 a cone for engaging said conical surface and thus forming a tight joint.

2. In a well packer, the combination of a sleeve, a bushing mounted thereupon, a hollow member extending through said bushing and into said sleeve, means carried by said hollow member for engaging said bushing and thus preventing the withdrawal of said hollow member from said sleeve, an expansible composite packer of 120 125 annular form encircling said hollow member, means for temporarily holding said packer member in a predetermined position relatively to said hollow member and for disengaging said packer member when said 130

hollow member is allowed to extend to its limit within said sleeve, said hollow member and said packer member being provided with mating inclined surfaces to be engaged

5 when said packer member is thus released, in order to expand the packer and form a tight joint.

3. The combination of a well casing, a packer of composite form mounted therein 10 and made of metal, a composite tubular member engaging said packer and forming a tight joint therewith so that said packer is capable of withstanding hydrostatic pressure, and an auxiliary packer mounted upon 15 said member of substantially tubular form for preventing the escape of gas around said member.

4. In a packer, the combination of a plurality of gripping sectors together having 20 the approximate form of a ring, a plurality of other gripping sectors also having together the form of a ring, all of said sectors being provided with slots and so disposed that a sector of one ring breaks the joint 25 between sectors of the other ring when the said slots of one ring are in registry with the slots of the other ring, and guide bolts extending through all of said slots.

5. In a packer, the combination of a plu-

rality of composite rings, each made up of 30 a number of gripping sectors movable relatively to each other, and metallic gaskets disposed between the rings.

6. The combination of a sleeve for resting upon the bottom of a well, a bushing 35 carried by said sleeve and disposed adjacent the top thereof, a hollow tubular composite member provided with a portion extending through said bushing and into said sleeve; a nut mounted upon said portion and located upon said sleeve for preventing the withdrawal of said portion from said sleeve, and a packer member encircling said portion and made of composite sectors movable 40 relatively to each other in order to enable 45 said packer member to be expanded and brought into engagement with the inner surface of a well casing by the movement of said tubular member relatively to said sleeve and bushing.

50 In testimony whereof I have signed my name to this specification in the presence of two subscribing witnesses.
